(57) CLAIM

The ornamental design for a foot care device, as shown and described.

DESCRIPTION

FIG. 1 is a top, front perspective view of a foot care device; FIG. 2 is a bottom, rear perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; and, FIG. 8 is a bottom plan view thereof.

The broken lines depicted in FIGS. 1-8 illustrate environmental matter that forms no part of the claimed design. The drawing contains symbolic break lines. It is understood that the appearance of any portion of the foot care device between the break lines forms no part of the claimed design.
